ANDROGENIC COMPOSITIONS

Arnold C. Ott, Kalamazoo, Mich., assignor to The Upjohn Company, Kalamazoo, Mich., a corporation of Michigan

No Drawing. Application June 6, 1949,
Serial No. 97,485

5 Claims. (Cl. 167—74)

1

This invention relates to therapeutically useful compositions having an exceptionally prolonged androgenic effect. More particularly, this invention relates to testosterone beta-cyclopentylpropionate and to androgenically active compositions containing the said ester.

The esterification of the 17-hydroxyl group of testosterone to produce certain esters having a greater and a more prolonged effect than testosterone is shown in United States Patent 2,109,400, and their injection in oil solutions is shown by Miescher, Wettstein and Tschopp, Biochem. J. 30, 1983 (1936). In these references, it is clearly shown that the maximum effectiveness of the esters there reported is reached in about 12 to 16 days after injection.

It has now been found that the novel compound, testosterone beta-cyclopentylpropionate, when injected in an oil solution, not only gives a maximum increase in the weight of the seminal vesicle of a castrated rat, much higher than that obtained with previously known esters of testosterone, but the effect persists for a period up to 30 days or longer following a single injection. These facts are more clearly shown in Tables I and II.

Table I

Castrated rats, received on the first experimental day, a quantity of the designated ester equivalent to five milligrams of testosterone, dissolved in peanut oil. At the end of each period of time indicated, five of the animals were sacrificed and the average weight of their seminal vesicles determined and recorded. Table I indicates the result obtained:

Compound	Weight of Seminal vesicle in milligrams after—						
	3 days	6 days	9 days	12 days	18 days	24 days	30 days
Testosterone beta-cyclopentylpropionate.....	22	82	223	454	565	513	443
Testosterone Propionate.....	22	80	169	208	61	65	57
Control castrated rats (no drug given).....	7	7	8	9	11	8	10

Table II

Castrated rats received on the first experimental day a quantity of the designated ester equivalent to five milligrams of testosterone, dissolved in peanut oil containing two percent aluminum monostearate. At the end of each period of time indicated, six of the animals were sacrificed and

2

the average weight of the seminal vesicles determined and recorded. The following results were obtained:

Compound	Weight of Seminal vesicle in milligrams after—						
	3 days	6 days	9 days	12 days	18 days	24 days	30 days
Testosterone beta-cyclopentylpropionate.....	23	97	270	522	625	494	343
Testosterone Propionate.....	24	96	131	137	50	50	37
Control castrated rats (no drug given).....	8	9	10	11	9	10	8

Testosterone beta-cyclopentylpropionate can be prepared by reacting testosterone with beta-cyclopentylpropionyl chloride (obtained from the action of thionyl chloride on beta-cyclopentylpropionic acid), in the presence of a tertiary base such as pyridine or dimethylaniline, and thereafter recovering the ester from the reaction mixture. The acid bromide, obtained by the action of thionyl bromide on beta-cyclopentylpropionic acid, may be used instead of the acid chloride, if desired. Beta-cyclopentylpropionate may also be prepared by other methods known to the art such as the ester interchange of a lower-alkyl ester of beta-cyclopentylpropionic acid with testosterone or by the azeotropic esterification of testosterone with beta-cyclopentylpropionic acid in the presence of benzene or toluene and para-toluene sulfonic acid, boron trifluoride or other like catalysts and reaction media.

The therapeutic oil solutions of the present invention can be prepared by dissolving the ester in ether, mixing the ether solution with a non-toxic, glyceride oil suitable for parenteral administration such as peanut, cottonseed, corn or sesame oil and removing the ether under reduced pressure. The concentration of the ester in the oil is limited only by its solubility and stable solutions containing about 500 milligrams of testosterone beta-cyclopentylpropionate per milliliter have been prepared. The use of ether or other similar low boiling non-reactive solvents speeds the solution of the ester in the oil, but their use is not essential, as the ester may be dissolved directly in the oil with stirring and gentle warming, if desired.

For some purposes, it is desirable to add aluminum monostearate to the oil solution to obtain a thixotropic gel. Thixotropic gels may be prepared by adding about two percent by weight per volume of oil of aluminum monostearate to an oil solution of the ester at room temperature.

The solution is then heated to about 120 degrees centigrade, held at that temperature for about ten minutes and the solution thereafter cooled. A thixotropic gel results which is solid at ordinary temperatures, but which will liquefy, if shaken.

The following examples are given to illustrate a method for preparing the products of this invention, but the said invention is not to be limited thereto.

Example 1.—Testosterone beta-cyclopentylpropionate

One and eight-tenths grams of beta-cyclopentylpropionyl chloride [J. Chem. Soc. (1939), page 1065] was added to a solution of 3.0 grams of testosterone in 7.0 grams of dry pyridine at a substantially uniform rate over a period of ten minutes. The reaction temperature was maintained at about five degrees centigrade during the addition. The temperature of the mixture was then raised to 26 degrees centigrade, and after being held there for four and one-half hours, the mixture was poured into 50 milliliters of cold aqueous 6-normal sulfuric acid and extracted four times with 25-milliliter portions of isopropyl ether. The ether extracts were combined, washed with dilute acid, water, dilute sodium bicarbonate and water. After drying, filtering and evaporating, light yellow crystals formed which were recrystallized from normal hexane. There was thus obtained 3.4 grams (80 percent of the theoretical yield) of testosterone beta-cyclopentylpropionate, melting at 101-102 degrees centigrade, $[\alpha]_D^{25} +76.4$ (chloroform).

Analysis:

Calculated for $C_{27}H_{44}O_3$ ...	C, 78.59	H, 9.77
Found -----	78.57	9.54

Example 2

A solution of three grams of dry, crystalline testosterone beta-cyclopentylpropionate in 20 milliliters of ethyl ether was added, with stirring, to 100 milliliters of U. S. P. XII cottonseed oil contained in a 300-milliliter balloon flask. The flask was fitted with a capillary ebullator attached to a stream of nitrogen, evacuated and warmed on a steam bath. After about an hour, all of the ether had been removed and a clear oil solution remained containing 30 milligrams per milliliter of testosterone beta-cyclopentylpropionate.

For the purpose of preservation, five milligrams of chlorobutanol per milliliter of solution may be added either to the hot oil or to the ether solution of the ester.

In a similar manner, solutions of testosterone beta-cyclopentylpropionate were prepared using sesame, peanut or corn oil.

Example 3

To vigorously stirred solution of three grams of testosterone beta-cyclopentylpropionate in 95 milliliters of peanut oil at 24 degrees centigrade, 1.9 grams of dry aluminum monostearate was added at a substantially uniform rate over a period of five minutes. The temperature of the mixture was then raised at a rate of 10 degrees centigrade per minute until a temperature of 120 degrees centigrade was obtained, and held at 120 degrees centigrade for 10 minutes. Stirring was discontinued and the clear syrupy product was allowed to cool at room temperature. There was thus obtained 100 milliliters of a thixotropic gel containing 30 milligrams of testosterone beta-cyclopentylpropionate per milligram. Upon agitation, a free-flowing liquid was obtained which is suitable for injection.

Various modifications may be made in the present invention without departing from the spirit or scope thereof, and it is to be understood that I limit myself only as defined in the appended claims.

I claim:

1. A therapeutic composition for parental administration having a prolonged androgenic effect, comprising: a sterile solution of testosterone beta-cyclopentylpropionate in a non-toxic vegetable oil.

2. A therapeutic composition for parental administration having a prolonged androgenic effect, comprising: a sterile solution of testosterone beta-cyclopentylpropionate and aluminum monostearate in a non-toxic vegetable oil.

3. A therapeutic composition for parental administration having a prolonged androgenic effect, comprising: a sterile solution of testosterone beta-cyclopentylpropionate in peanut oil.

4. A therapeutic composition for parental administration having a prolonged androgenic effect after a single injection comprising a sterile solution of testosterone beta-cyclopentylpropionate and about two percent by weight of aluminum monostearate of the volume of the oil used in peanut oil.

5. Testosterone beta-cyclopentylpropionate.
